LOOPER MECHANISM FOR SEWING MACHINES

Frank A. Kucera, Chicago, Ill., assignor to Union Special Machine Company, Chicago, Ill., a corporation of Illinois

Application February 19, 1937, Serial No. 126,584

8 Claims. (CL 112—200)

This invention relates to looper mechanism for sewing machines; and it is concerned more particularly with looper mechanism for feed-off-the-arm sewing machines, of the general type featured in United States Patent No. 1,912,959, granted to Frederick F. Zeier et al., July 6, 1933.

With the patented arrangement, the looper carrier must be axially shifted on the looper shaft before it can be independently turned part way about said shaft to render the loopers accessible for ready threading. Thus, in the event that the sewing machine is started without restoration of the looper carrier to its normal position, the loopers are apt to be injured or broken through impact with the feed dog or other contiguous parts of the machine mechanism which they ordinarily clear when in their normal planes of operation.

My invention has for its chief aim to preclude contingencies of the sort referred to. This objective I realize in practice as hereinafter more fully disclosed, through provision of holder means whereby the looper carrier is restrained against endwise movement on the looper shaft, and associated latch means whereby said carrier is locked to the shaft with capacity for being released so that it can be swung to a limited extent about said shaft for threading of the loopers.

Another object of my invention is to attain the above advantages in a looper mechanism of the character indicated embodying a latch means which is of simple and compact construction and easier to operate than latch devices heretofore designed to serve a similar purpose.

Other objects and attendant advantages will appear from the following detailed description of the attached drawings, whereof Fig. I is a fragmentary view showing the front end of the work-supporting arm of a feed-off-the-arm sewing machine partly in side elevation and partly in longitudinal section, with the looper mechanism of my invention exposed.

Fig. II is a transverse section taken as indicated by the arrows II—II in Fig. I but with the loopers shown in their normally retracted positions.

Fig. III is a view like Fig. II but with the loopers swung back beyond their normal retracted positions for threading.

Fig. IV is a plan view of the looper assembly with the loopers in the fully advanced or needle loop-taking positions.

Fig. V is a view partly in elevation and partly in section taken as indicated by the arrows V—V in Fig. IV.

Fig. VI is a fragmentary sectional view taken as indicated by the arrows VI—VI in Fig. V.

Figs. VII and VIII are perspective views of two component elements of my improved looper mechanism.

Fig. IX is a fragmentary detail section taken as indicated by the arrows IX—IX in Fig. II, showing the latch means for the looper carrier in normal locked position; and

Fig. X is a similar view taken as indicated by the arrows X—X in Fig. III and showing the looper carrier latch in released position.

With more specific reference to these illustrations, the numeral 1 designates the looper shaft, which, as shown, extends longitudinally through the hollow of the tubular horizontal work-supporting arm 2 of the sewing machine, said shaft being journaled in bearings whereof one is indicated at 3. Under the influence of suitable actuating mechanism (not shown) the shaft 1 is oscillated and reciprocated endwise to impart loop-taking and shedding, and needle-avoiding movements to the loopers 4 (of which there are three in the present instance) incident to coaction of the latter with as many needles 5 to form a multiple row seam after a manner well known in the art. The loopers 4 operate beneath a throat plate 6 which is secured by one or more screws 7 to the top of the work-supporting arm 2, and are protected by a cap 8 which is removably held in place over the end of said arm by a spring pressed keeper shown at 9 in Fig. I. Above the throat plate 6 is a presser foot 10 which opposes a feed dog 11 mounted upon the forward yoke-like end 12a of a feed bar 12 (see Fig. II), which latter extends longitudinally above the shaft 1 within the work-supporting arm 2. By suitable means partly shown at 13, the feed bar 12 is moved back and forth and up and down, with attendant impartation of the necessary feed and lift movements to the feed dog 11.

In accordance with the present invention, the loopers 4 are curved concentrically with the axis of the shaft 1 and supported in circumferentially offset relation by a carrier 15 which is separately illustrated in perspective in Fig. VIII. As shown in Fig. VI, the tubular portion 16 of the carrier 15 freely embraces a holder in the form of a sleeve 17, which holder is separately illustrated in Fig. VII, and which is secured by screws 18 to the forward end of the shaft 1 with capacity for both longitudinal and rotative adjustment thereon. The carrier 15 is held against endwise movement between a shoulder 19 of the sleeve 17 and a nut collar 20 threadedly engaging the outer end of

said sleeve. An additional nut collar 21 is relied upon to prevent accidental rotation of the collar 20 after assembling of the parts. As shown in Figs. I, IV, V, and VI, the loopers 4 have anchorage shanks 22 with apertures for passage of individual securing screws 23, said shanks being concaved as at 24 to fit the curved surface 25 of a sector-shaped projection 26 of the carrier 15 and together aggregating a width to completely fill the interval between the end flanges 27 of said projection, see Figs. I and VI.

Set in a longitudinal recess 28 in the surface of the sector projection 26 and secured to the latter by screws 29, is a block 30. From Figs. IV-VIII, it will be noted that the carrier 15 and the sleeve 17 are cut away respectively at 15a and 17a, the resulting voids being in registry and providing a clearance opening through which the screws 29 are passed incident to assembling the block 30 with said carrier. The voids 15a and 17a also are necessary for clearance of the needles 5 during the descent of the latter. The block 30 has a lengthwise bore 31 (Figs. IX and X) for guidance of a latch pin 32 which passes through an arcuate slot 33 in an integrally formed radial wing 35 of the sleeve 17, said slot being concentric with the shaft 1. At its rear end, the latch pin 32 has a tapered head 36 which normally occupies a notch-like enlargement 37 at one end of the slot 33 in the wing 35, as shown in Figs. II, V and VI. The front end of the latch pin 32 is threaded as at 38 for engagement by a thumb nut 39 which has a hollow prolongation 40 fitting a concentric recess 41 at the corresponding end of the bore 31 in the block 30. A helical compression spring 42 housed partly within the hollow of the thumb nut 39 and partly within the recess 41 of the block 30, tends to urge the latch pin 32 outward, i. e., leftward in Figs. IX and X. Attached to the block 30 by screws 43 is a guide 45 with eyes 46 respectively in line with the thread grooves 47 of the loopers 4, by which the looper threads are directed as shown in dot and dash lines in Figs. I and II after passing through an opening 48 in the bearing 3 enroute from a source of supply, not shown.

With the head 36 of the latch pin 32 engaged in the enlargement 37 of the slot 33 in the wing 35 as shown in Figs. II, V, IX, the carrier 15 is locked to the sleeve 17 and the loopers 4 thereby maintained fixed in their normal positions circumferentially of the shaft 1. Accordingly, by oscillation of the shaft 1, the loopers 4 are swung back and forth between the limits of retraction and advance respectively, shown in Figs. II and V incident to stitch-formation.

When threading of the loopers 4 is necessary, the cap 8 is first removed from the end of the work-supporting arm 2, and the machine operated by hand to bring said loopers to the normal retracted position shown in Fig. II. The thumb nut 39 is thereupon grasped between the fingers of one hand and thrust inward against the force of the spring 42 to dislodge the head 36 of the latch pin 32 from the notch 37 in the end of the arcuate slot 33 in the wing 35 of the sleeve 17 and thereby free the looper carrier 15. With this accomplished, the thumb nut 39 is shifted clockwise in Fig. II to advance the latch pin 32 along the slot 33 in the wing 35 with attendant movement of the loopers 4 about the shaft 1 from the position of Fig. II to that of Fig. III where their eyes are conveniently accessible for threading. After threading of the loopers 4, the above procedure is reversed, that is to say: the thumb nut

39 is grasped and swung anti-clockwise from the position of Fig. III to that of Fig. II incident to which the head 36 of the latch pin 32 will be automatically drawn back into the notch 37 of the arcuate slot 33 in the wing 35 under the action of the spring to relock the carrier 15 to the sleeve 17, with consequent restoration of the loopers 4 to the normal circumferential relation with respect to the shaft 1. Upon replacement of the end closure cap 8, the machine is once again ready for operation.

Having thus described my invention, I claim:

1. Looper mechanism for sewing machines comprising a shaft; a holder member fixed on the shaft; a looper carrier rotatively free on the shaft but confined against axial-movement relative to the holder member; and latch means whereby the looper carrier is normally locked to the holder member for movement with said shaft, said latch means being releasable to permit limited shifting of the carrier circumferentially of the shaft in relation to the holder member.

2. Looper mechanism for sewing machines comprising a shaft; a holder member in the form of a sleeve fixed on the shaft with capacity for rotative and endwise adjustment on the shaft; a looper carrier on the sleeve confined against axial movement relative to the holder member; and latch means whereby the looper carrier is normally locked to the holder member for movement with the shaft, said latch means being releasable to permit limited shifting of the carrier circumferentially of the shaft in relation to the holder member.

3. Looper mechanism for sewing machines comprising a shaft; a holder member fixed on said shaft and having a concentric arcuate slot with an enlargement at one end thereof; a looper carrier rotatively free on the shaft but confined against axial movement relative to the holder member; a latchpin on the carrier passing through the arcuate slot of the holder member and having a head normally in engagement with the enlargement of the slot, said pin being axially shiftable for dislodgment of its head from the slot enlargement to permit limited circumferential shifting of the looper carrier about the shaft in relation to the holder member.

4. Looper mechanism for sewing machines comprising a shaft; a holder member in the form of a sleeve adjustably fixed on said shaft, said sleeve having a radial wing with an arcuate slot therein concentric to the shaft and terminating at one end in an enlargement; a looper carrier rotatively free on the sleeve but confined against axial movement relative to the holder member; and a latch pin on the carrier passing through the arcuate slot in the wing aforesaid and having a head normally in engagement with the enlargement of the slot, said latch pin being axially shiftable for dislodgment of its head from the slot enlargement to permit limited shifting of the looper carrier circumferentially of the shaft in relation to the sleeve.

5. Looper mechanism for sewing machines comprising a shaft; a looper carrier mounted on the shaft and having a curved surface concentric with said shaft between end flanges; a plurality of loopers having anchorage shanks which together aggregate the space between the end flanges of the carrier and which are concaved to fit the curved surface of said carrier; and means whereby the loopers are individually secured to the carrier.

6. Looper mechanism for sewing machines comprising a shaft; a holder member fixed on the shaft; a looper carrier rotatively free on the shaft but confined against axial-movement relative to the holder member; latch means whereby the looper carrier is normally locked to the holder member for movement with said shaft, said latch means being releasable to permit limited shifting of the carrier circumferentially of the shaft in relation to the holder member; and a looper thread guide movable with the carrier.
7. Looper mechanism for sewing machines comprising a shaft; a holder member fixed on the shaft; a looper carrier rotatively free on the shaft but confined against axial movement relative to the holder member; and latch means whereby the looper carrier is normally locked to the holder member for movement with said shaft, said latch means constituting a manipulating element, which, when moved in one direction, effects release of the carrier from the holder, and which, when moved in another direction, causes

said carrier to be shifted circumferentially of the shaft in relation to the holder.

8. Looper mechanism for sewing machines comprising a shaft; a holder member in the form of a sleeve adjustably fixed on said shaft, said sleeve having a radial wing with an arcuate slot therein concentric to the shaft and terminating at one end in an enlargement; a looper carrier rotatively free on the sleeve but confined against axial movement relative to the holder member; and a latch pin on the carrier passing through the arcuate slot in the wing aforesaid and having a head normally in engement with the enlargement of the slot, said latch pin constituting a manipulating element which, when moved axially, causes dislodgment of its head from the slot enlargement with attendant release of the carrier, and which, when moved laterally, causes said carrier to be shifted circumferentially of the shaft in relation to the sleeve within the limits of the slot aforesaid.
